CARL B. BORMANN, OF WESTWOOD, NEW JERSEY

BURGLAR-PROOF ARRANGEMENT FOR THE PROTECTION OF BANK CLERKS

Application filed July 1, 1930. Serial No. 465,155.

My invention has for its object to provide a burglar-proof arrangement for protecting bank clerks against hold-up men. The arrangement is so designed that the bank clerk **5** is at all times effectively guarded against sudden attacks or bullets while left entirely free to transact any business with the person in front of his window.

To this end I provide a movable guard in **10** front of the window, behind which the clerk has his place so that said guard when occupying its raised position prevents any access to the opening below the window, a swinging guard-plate suspended back of the window so as to prevent any bullet from reaching the clerk when said movable guard is in its lowered position, and a flat slide or tray arranged to operate said movable guard and equipped with an upward extension to **15** bear against said swinging guard-plate, so as to entirely close the opening below the window, when the movable guard in front of the window is in the lowered position. The window itself is made of bullet-proof **20** glass and mounted in the hollow frame so as to leave on either side an open space for the sound-waves to pass from the bank clerk to the person outside the window and vice versa.

25 On the annexed drawings, on which, for the sake of a complete understanding of the invention, I have shown, by way of illustration, an embodiment thereof, Fig. 1 is a vertical sectional view through a bank-clerk's window showing the new arrangement with the movable guard in raised position; Fig. 2 is a horizontal section along line 2—2 in Fig. 1, the new arrangement being shown **30** in top plan view; Fig. 3 is a fragment of the window and the arrangement as viewed from the left in Fig. 1; Fig. 4 is a view similar to Fig. 2, showing the parts in a different position, i. e. with the movable guard in the lowered position, the section being taken along line 4—4 in Fig. 5; Fig. 5 is a **35** similar view as Fig. 1, showing the movable guard in its lowered position and the slide or tray in its extreme forward position. Fig. **40** 6 is a sectional detail to more clearly show

the mounting of the glass-pane, the section being taken along line 6—6 in Fig. 5.

In Figs. 1 and 5, 1 denotes a portion of the partition which separates the clerical force from the public, forming the cage, in which **45** the clerk takes his position. 2 is the frame containing the window-mounting 3 which, as will be more clearly seen from Figs. 2 and 4, is made up of U-shaped uprights 4 and 5, in which is mounted a bullet-proof window **50** pane 6 which is held in the said uprights by short bolts 7, washers 8 being interposed as shown. As will be clearly seen from Figs. 2 and 4, the width of the window pane is so selected that an open space is left all **55** around to permit the sound-waves to pass from the inside of the cage to the outside, and vice versa, so as to enable conversation to be carried on. Against the lower ends of the said uprights bears a horizontally **60** disposed glass-plate 9 which is held in a frame-part 10 having a depending portion 11.

At 12 is shown a movable guard of sector-shaped cross-section made of heavy sheet-metal. This guard is pivotally held in the **65** frame 2 at 13 and when in its raised position is adapted to bear with its cylindrical surface against the depending portion 11 of the frame-part 10. To the flat portion 14 of said **70** movable guard 12 is secured at one end there-of an arm 15 for the purpose hereafter described.

On a rail shown at 16 is pivoted a lever-arm 17 in such a position relative to said arm 15 as to cooperate therewith when the **75** movable guard 12 has been moved to its raised position shown in Fig. 1. A helical spring shown at 18 in Figs. 1 and 5 tends to move the lever-arm 17 to the position shown in Figs. 1 and 2. At 19 and 20 are shown horizontally disposed guide-rails for a movable tray shown at 21, which, at its inner end, is provided with a handle 22 and an upward projection 23. To the bottom of said tray is secured a straight cam-piece 24. At 25, a **80** slot is shown in the tray adapted to receive the arm 15 of the movable guard 12, as the tray is outwardly moved toward the right in Figs. 1 and 2, by means of its handle 22.

At 26 is shown a guard-plate, also made of **85**

heavy sheet-metal and pivotally suspended from a rod 27, so that the lower portion of said guard-plate projects downwardly over part of the open space below the glass-plate 9.

From the foregoing description, the operation of the device will be readily understood.

The various parts, it will be assumed, occupy the positions shown in Figs. 1 and 2,

- 10 in which the movable guard 12 is shown raised, while the tray 21 occupies its extreme inward position, the guard-plate 26 hanging straight down from the rod 27. In this position, all access from the outside of the cage
- 15 is effectively prevented by the movable guard 12 closing the entire opening and being held in said position by the spring 18, by means of the lever arm 17 extending over the arm 15 of the movable guard 12. Now, when a
- 20 person appears in front of the window and wishes to pass anything to the bank clerk, seated behind the window, the clerk pushes the tray 21 outward, that is, toward the right in Fig. 1, the tray being evenly guided 25 by the guide-rails 19 and 20. As the slot 25 in the tray passes over the arm 15, the latter projects into said slot and consequently, as the movement of the tray toward the right in Fig. 1 continues, the guard 12, by means 30 of said arm 15 is gradually turned into the lowered position shown in Fig. 5, the arm 15 of said guard then assuming the upright position shown in Fig. 5. By the lowering of the guard 12 the open space under the 35 glass plate 9 is exposed and any papers, e. g. a pass-book, or the like, can be placed on the tray 21, while the latter occupies the position shown in Fig. 5. As the tray 21 was being moved into this position, the cam 24 on 40 the bottom of said tray pushed aside the lever arm 17 against the tension of spring 18 to permit the arm 15 of the movable guard 12 to completely enter the slot 25 in the tray, and while the lever arm 17 was thus pushed 45 aside by the cam 24, the helical spring 18 became stretched and thus was placed under tension.

While the open space under the glass-plate 9 is exposed, any access to the inside of 50 the clerk's cage is yet effectively prevented by the straight guard plate 26 against which bears the upright projection 23 of the tray 21, as clearly shown in Fig. 5. The guard-plate 26 being made of heavy sheet-metal, 55 no bullet can reach the clerk from the outside. As the tray 21 is pulled back by the clerk, or in other words, moved again toward the left in Fig. 5, the arm 15 of the front guard 12 is engaged by the slot 25 60 in the tray which thereby forces the arm 15 down, thus gradually raising the guard 12 to the position shown in Fig. 1. While the tray is being returned to the position shown in Fig. 1, the straight cam 24 on the bottom of 65 the tray is drawn away from the lever-arm

17, and the previously tensioned spring 18 now moves the lever-arm back over the arm 15, as shown in Fig. 1, so as to hold the said arm 15 down and thereby the movable guard 12 in its raised position. And as the upright portion 23 of the tray 21 moves away from the suspended guard-plate 26, the latter again automatically returns to the straight position shown in Fig. 1.

From this it will be seen, that the bank clerk is at all times most effectively protected against any intrusion from the outside and against any fire-arms which might be levelled against him.

The bullet-proof glass-pane 6 being 80 mounted in a hollow frame with an open space all around it, sound-waves can freely pass to the outside of the window, and vice versa.

Needless to say, the embodiment as shown 85 in the drawings, can be modified in various ways without departing from the invention as above described, the object being to at all times effectively protect the bank-clerk against any sudden attacks from burglars, or 90 hold-up men.

I claim:

1. In combination with a bank-clerk's window, a movable guard pivotally mounted in front of the window and provided with an 95 arm, a spring-controlled means normally engaging said arm to thereby hold said guard in raised position, a movable tray having a slot disposed to engage said arm, and a cam on the bottom of said tray adapted to engage 100 said spring-controlled means so as to release said arm permitting said movable guard to be moved to its lowered position.

2. In combination with a bank-clerk's window, a movable guard pivotally mounted 105 in front of the window and provided with an arm, a spring-controlled means normally engaging said arm to thereby hold said guard in raised position, a movable tray having a slot disposed to engage said arm, and a cam on the bottom of said tray adapted to engage 110 said spring-controlled means so as to release said arm permitting said movable guard to be moved to its lowered position; and a guard plate suspended back of the window, so as to 115 cooperate with an upright projection on said tray to prevent any access to the inside of the window.

3. In combination with a bank-clerk's window, a movable guard pivotally mounted 120 in front of the window and provided with an arm, a spring-controlled means normally engaging said arm to thereby hold said guard in raised position, a movable tray having a slot disposed to engage said arm, and a cam on the bottom of said tray adapted to engage 125 said spring-controlled means so as to release said arm permitting said movable guard to be moved to its lowered position, and a guard plate suspended back of the window so as to 130

cooperate with an upright projection on said tray to prevent any access to the inside of the window, and means for guiding said tray during its to and fro movement.

5 4. In combination with a bank-clerk's window, a movable guard situated in front of said window and adapted to be raised and lowered, a guard plate suspended in the back of said window so as to project into the open
10 space below the same, a sliding member and means operatively connecting said member with said movable guard, spring-controlled means for securing said movable guard in its raised position and means on said sliding
15 member for operating said spring-controlled means.

In testimony whereof I affix my signature.

CARL B. BORMANN.
